UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 29,211, dated August 9, 1898.

Application filed July 2, 1898. Serial No. 685,059. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

The leading feature of my design is clearly shown in the accompanying drawing, which represents a battleship in the center sur-

rounded by a wreath, an eagle at top, a United States flag on one side, a Cuban flag on the other side, the whole surrounded by an ornamental border, as shown.

Having as above fully described my invention, what I claim as new, and desire to secure by Letters Patent, is—

The design for a woven fabric, as shown and described.

W. T. SMITH.
